AIRPLANE TYPE KITE

Alphonse J. Tomezyk, Chicago, and Melvin C. Spreitzer, Des Plaines, Ill.

Application March 21, 1947, Serial No. 736,210

5 Claims. (Cl. 244—154)

1

The present invention relates generally to kites. More particularly the invention relates to that type of kite which is shaped or designed to simulate a conventional single wing variety airplane, consists of a longitudinally extending beam, an empennage in the form of horizontal and vertical fins, a pair of complementary, oppositely extending wing sections on the front end of the beam, and a body or fuselage simulating strip along the beam, and is so constructed that the wing sections and the vertical fin are detachable in order that the kite may be transported or stored in knock-down form and when in such form is capable of being retained in a small sized container.

One object of the invention is to provide a kite of this type which is an improvement upon, and has certain inherent advantages over, previously designed kites of the same general character and is characterized by the fact that it is essentially simple in design and construction and possesses extremely desirable flying characteristics.

Another object of the invention is to provide an airplane type kite of the last mentioned character in which each of the wing sections comprises in addition to a covering a single or one-piece U-shaped frame forming wire and is connected to the front end of the longitudinally extending beam by way of a pair of brackets to which the ends of the wire are removably attached.

Another object of the invention is to provide a kite of the type and character last mentioned in which the coverings of the wing sections are in the form of elongated envelopes which have open inner ends, are adapted to be mounted in place by sliding them inwards around the U-shaped frame forming wires, and provide spaced apart upper and lower surfaces for the wing sections.

Another object of the invention is to provide an airplane type kite of the type and character under consideration in which the inner open ends of the envelopes constituting the coverings for the wing sections are provided with simple and novel means for securing them together adjacent the front end of the longitudinally extending beam.

A further object of the invention is to provide a kite of the aforementioned type in which the horizontal fin of the empennage and the body or fuselage simulating strip are formed of a single piece of comparatively stiff cardboard and are bonded or adhesively connected to the bottom face of the longitudinally extending beam.

A still further object of the invention is to pro-

2

vide an airplane type kite which is generally of new and improved construction and by reason of its specific design is capable of being produced at a comparatively low cost.

Other objects of the invention and the various advantages and characteristics of the present airplane type kite will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective of an airplane type kite embodying the invention, certain parts being broken away for purposes of illustration;

Figure 2 is an enlarged fragmentary plan view of the front end of the kite, illustrating in detail the manner in which the ends of the U-shaped frame forming wires of the wing sections are detachably connected to the front end of the longitudinally extending beam, and also the manner in which the inner open ends of the envelopes constituting the coverings for the wing sections are connected together;

Figure 3 is a vertical transverse section through one of the wing sections;

Figure 4 is an enlarged side view of one of the brackets whereby the wing sections are detachably connected to the front end of the longitudinally extending beam; and

Figure 5 is an enlarged vertical transverse section taken on the line 5—5 of Figure 1.

The airplane type kite which is shown in the drawing constitutes the preferred form or embodiment of the invention. It is adapted to be flown in the same manner as any conventional kite and, as shown in the drawing, is shaped or designed to simulate a monoplane, i. e., a conventional single wing variety airplane. As its principal components or parts the kite comprises a longitudinally extending beam 6, an empennage or tail structure 7, a pair of wing sections 8, and a body or fuselage simulating strip 9.

The beam 6 is preferably formed of wood. It constitutes the main supporting or reinforcing instrumentality of the kite and is square in cross section.

The empennage 7 serves as the tail of the kite and consists of a horizontally extending fin 10 and a vertically extending fin 11. Both are formed of comparatively stiff cardboard. The

horizontal fin 10 is flat and simulates in general outline or contour the horizontal fin or stabilizer and the elevators of the empennage of a conventional airplane. The central portion of the horizontal fin 10 underlies the rear end of the longitudinally extending beam 6 and is adhesively connected, cemented or otherwise suitably bonded to the bottom face of the beam. The vertical fin 11 overlies the horizontal fin 10 and is shaped to simulate the vertical stabilizer or fin and the rudder of the empennage of a conventional airplane. It is centrally positioned with respect to the horizontal fin and extends upwards from, and is suitably connected to, the rear end of the longitudinally extending beam 6. Preferably the vertical fin 11 is connected to the beam by having the bottom margin thereof confined and fitting within a vertical longitudinally extending slit 12 in the rear end of the beam. This arrangement makes it possible to detach the vertical fin from the beam in connection with transportation or storing of the kite as a whole. It is contemplated that the kite will be merchandised in knock-down form and assembled for use. If, in connection with assembly, it is desired permanently to secure the vertical fin 11 in place it is only necessary to cement or adhesively connect the bottom margin of such fin to the faces of the beam that define the slit 12. As an alternative, brads (not shown) may be driven transversely through the slotted rear end of the beam 6 and positioned so as to pass through the confined lower margin of the fin.

The wing sections 8 are located at the front end of, and project outwards in opposite directions from, the front end of the longitudinally extending beam 6 and are complementary. They serve as the main supporting surfaces for the kite and, as hereinafter described, are detachably connected to said front end of the beam 6. Each wing consists of a single or one-piece U-shaped frame forming wire 13 and a cover forming envelope 14. When the wing sections 8 are in attached or connected relation with the beam the ends of the wires 13 are disposed adjacent the front end of the beam. The front legs of the wires form the front spars of the wing sections and the rear legs of the wires form the rear spars. The curved or rounded intermediate portions of the wires constitute the tip portions of the frames of the wing sections. The ends of the wires 13 fit slidably within the ends of a pair of tubes 15. The latter overlie and extend transversely of the front end of the beam 6. They are spaced horizontally apart and have the central portions thereof connected to the upper central portions of a pair of sleeve-like brackets 16. As best shown in Figures 4 and 5, the brackets 16 extend around and grip frictionally the front end of the beam 6. It is contemplated that in connection with fabrication of the kite the brackets 16 will be slid into place on the front end of the beam 6. If desired the tubes 15 may be formed integrally with the sleeve-like brackets 16 as shown in Figure 4. The ends of the U-shaped wires 13, as heretofore pointed out, fit slidably within the ends of the tubes 15 and hence permit the wing sections 8 to be removed or detached simply by shifting them outwards with respect to the beam 6. The wires 13 are bent upwards adjacent the ends thereof in order that the wing sections 8 when in place have the desired or proper dihedral. Preferably the rear legs of the U-shaped wires 13 extend at true right angles to the beam 6 and the front legs have a rearward

sweepback. The ends of the front legs of the wires are, however, arranged in parallel relation with the ends of the rear legs of the wires 13 in order that all ends may be readily inserted into, and withdrawn from, the ends of the tubes 15. The envelopes 14 constituting the coverings of the wing sections 8 are shaped conformably to the frames 13. They are formed of imporous or fluid impervious paper and consist of upper sheets 17 and lower sheets 18. The rear, outer end, and front marginal portions of the upper and lower sheets are pasted together. The inner end margins of the sheets are not, however, pasted together and hence permit the envelopes to be slid inwards into surrounding or assembled relation with the U-shaped wires 13 in connection with assembly of the wing sections. By providing the front legs of the wires 13 with a rear sweepback sliding of the envelopes 14 into place is facilitated. The length of the envelopes 14 is such that when the envelopes are in place the open inner ends terminate adjacent the ends of the frame forming wires 13. In connection with mounting or attachment of the wing sections the ends of the wires 13 are first inserted into the ends of the tubes 15. Thereafter the envelopes 14 are slid inwards so that the open inner ends thereof surround the ends of the tubes 15. In order to connect together the wing sections after assembly thereof with respect to the tubes 15 the inner end margin of the upper sheet 17 of one of the envelopes is provided with a flap 19. This flap is adapted to overlap the inner end marginal portion of the upper sheet of the other envelope and embodies on its under surface a coating of pressure sensitive variety or other adhesive whereby it may be secured in place. The upper and lower sheets 17 and 18 of the covering forming envelopes form respectively the upper and lower surfaces of the wing sections. By having the upper sheets as well as the lower sheets and spacing the sheets apart by the U-shaped frame forming wires 13 the wing sections have exceptionally pronounced high lift characteristics and thus permit the kite in connection with flight thereof to attain comparatively high altitudes. When it is desired to remove the wing sections 8 in connection with storage of the kite the flap 19 is removed or released. Thereafter the two wing sections are shifted outwards so as to slide the ends of the wires 13 out of the ends of the tubes 15 on the sleeve-like brackets 16.

The body or fuselage simulating strip 9 underlies and extends lengthwise of the front end and the central portion of the beam 6. It is formed of comparatively stiff cardboard and preferably has the rear end thereof formed integrally with the front end of the horizontal fin 10 of the tail structure or empennage 7. The central or medial portion of the strip 9 is cemented, adhesively connected or otherwise fixedly secured to the bottom face of the beam 6. As shown in Figure 1 the side portions of the strip 9 project outwards of the sides of the beam 6 with the result that the strip serves as an additional supporting surface for the kite. As shown in the drawing, the strip 9 is flat and has a rounded front end which terminates inwards of the front end extremity of the beam 6.

In flying the kite a belly string 20 and a main string 21 are employed. One end of the belly string is connected to the front end of the beam 6 and the other end is connected to the rear end of the strip 9. The kite end of the main string 21 is connected to the belly string by way of a loop

and is so positioned with respect to the belly string that the kite when subjected to forward propulsion into the wind will fly upwards.

The herein described airplane type kite, due to its design and construction, is efficient and possesses highly desirable flying characteristics. It is capable of being produced at a comparatively low cost and may be assembled and dismantled with facility.

The invention is not to be understood as restricted to the details set forth since these may be modified within the scope of the appended claims without departing from the spirit and scope of the invention.

Having thus described the invention what we claim as new and desire to secure by Letters Patent is:

1. As a new article of manufacture, an airplane type kite comprising a longitudinally extending beam provided at its rear end with a fin variety tail structure, a pair of complemental wing sections projecting outwards in opposite directions from the front end of the beam and each embodying an elongated one-piece U-shaped frame-forming wire arranged so that the curved part thereof is outermost, tapered outwards in the direction of said curved part, and having the ends thereof connected to said front end of the beam, and an elongated covering-forming envelope shaped conformably to, and extending over, the wire, consisting of one-piece upper and lower sheets of imporous paper with the front, outer end, and rear margins thereof pasted together, and having the inner end thereof open in order that it may be slid onto and off of said wire, and releasable means for securing the inner ends of the envelopes in place adjacent said front end of the beam.

2. As a new article of manufacture, an airplane type kite comprising a longitudinally extending beam provided at its rear end with a fin variety tail structure, a pair of complemental wing sections projecting outwards in opposite directions from the front end of the beam and each embodying an elongated one-piece U-shaped frame-forming wire arranged so that the curved part thereof is outermost and having the rear leg thereof extending at right angles to the beam and its front leg inclined rearwards so that it is outwardly tapered, and having the inner ends of said rear and front legs connected to said front end of the beam, and an elongated covering-forming envelope shaped conformably to, and extending over, the wire, consisting of one-piece upper and lower sheets of thin, imporous, flexible material with the front, outer end and rear margins thereof bonded together, and having the inner end thereof open in order that it may be slid onto and off of said wire and releasable means for securing the inner ends of the envelopes in place adjacent the front end of the beam.

3. As a new article of manufacture, an airplane type kite comprising a longitudinally extending beam provided at its rear end with a fin variety tail structure, a pair of complemental wing sections projecting outwards in opposite directions from the front end of the beam and each embodying an elongated U-shaped frame

arranged so that the curved part thereof is outermost and having the ends thereof connected to said front end of the beam, and an elongated covering-forming envelope shaped conformably to, and extending over, the frame and having the inner end thereof open in order that it may be slid onto and off of said frame, and releasable means for securing together the inner open ends of the envelopes, consisting of a flap connected to the inner open end of one of the wing sections, adapted to lap the inner open end of the other wing section, and provided with an instrumentality for attaching it to the last mentioned end.

4. As a new article of manufacture, an airplane type kite comprising a longitudinally extending beam provided at its rear end with a fin variety tail structure, a pair of complemental wing sections projecting outwards in opposite directions from the front end of the beam and each embodying an elongated U-shaped frame arranged so that the curved part thereof is outermost and having the ends thereof connected to said front end of the beam, and an elongated covering-forming envelope shaped conformably to, and extending over, the frame and having the inner end thereof open in order that it may be slid onto and off of said frame, and releasable means for securing together the inner open ends of the envelopes, consisting of a flap connected to the inner open end of one of the wing sections, adapted to lap the inner open end of the other wing section, and provided with an adhesive coating for bonding it to the last mentioned end.

5. As a new article of manufacture, an airplane type kite comprising a longitudinally extending beam of rectangular cross section, a tail structure mounted on the rear end of the beam and including a thin, flat, comparatively stiff horizontal fin having the central portion thereof underlying and connected to the bottom face of said beam, a pair of complemental wing sections connected to, and projecting outwards in opposite directions from, the upper portions of the front end of the beam, and a thin, flat, comparatively stiff body or fuselage simulating strip connected to, and underlying, the front end and central portion of the beam and having its rear end formed integrally with the front end of the horizontal fin and its front portion underlying and extending downwardly of the inner ends of the wing sections.

ALPHONSE J. TOMCZYK.
